UNITED STATES PATENT OFFICE.

ARTHUR C. ISBELL, OF IVORYTON, CONNECTICUT.

APPARATUS FOR GUIDING AUTOMOBILES INTO POSITION FOR SERVICE.

Application filed June 30, 1928. Serial No. 289,510.

This invention relates to apparatus which is designed to automatically guide an automobile over a washing, greasing or repair pit in a garage, or onto a washing, greasing, repair or loading trestle at a service station, or onto an elevator, so that all danger of the car dropping into the pit, or off from the trestle, or from hitting the sides of the elevator, will be eliminated regardless of the angle of approach and thus injury to the car or to an attending mechanic will be avoided and the car will be located in position to facilitate greasing, repairing, washing or loading.

In attaining this end a frame adapted to be set into a garage floor, or other floor or platform, at the front of the pit, trestle or elevator, is provided with angularly arranged freely rotating rollers the widest spread of which is approximately the same as the distance apart of the guard rails that are usually located along the edges of a pit or are fastened on a trestle. Below these deflecting rollers is a table which is supported by rolls on shafts held in bearings in the frame in such manner that the table is free to move from side to side. Fastened on the top of and movable with the table is an apron of such size that it will cover the openings between the ends of the table and frame in all positions of the table.

In the accompanying drawings Fig. 1 shows a plan of one form of the apparatus located in the floor in front of a pit in a garage or service station. Fig. 2 is a section on the plane indicated by the dotted line 2—2 on Fig. 1. Fig. 3 is a section on the plane indicated by the dotted line 3—3 on Fig. 1.

The frame 1 which is rectangular in outline is desirably formed of T-iron, and is designed to be set into an opening that extends across the front of the pit or trestle, with the outer flanges resting on the floor or platform at the edges of the opening. The deflecting rollers 2, the angular relation of which may be varied as desired, are shown as supported at their spread ends by blocks 3 fastened to one side rail of the frame and at their adjacent ends by a block 4 fastened to the other side rail of the frame. The blocks so support these rollers that their widest distance apart is approximately the width apart of the guard rails 5 which are shown along the edges of the pit 6.

Extending transversely across the frame and supported at their ends by the downwardly extending flanges of the side rails are shafts 7 on which are rolls 8. Mounted on these rolls is the table 9, the width of which is approximately the same as the width of the opening in the frame and the length of which is somewhat shorter than the opening in the frame so that the table 65 may move longitudinally in the frame on these rolls. The table may be made of cast iron with reinforcing webs 10 to give it sufficient strength to support an automobile. Fastened on top of the table is an apron 11 70 that extends sidewise beyond the ends of the table a sufficient distance to cover the openings between the ends of the table and the end rails of the frame at all times as the table is moved from side to side. Springs 75 12 may be attached between studs 13 that extend downward from the under side of the table, and the end rails of the frame to normally retain the table in central position in the frame. 80

With this apparatus in place when a car is driven toward the pit, or trestle, or elevator, at any angle and one of its front wheels encounters one of the oblique deflecting rollers fixed on top of the frame, that roller wedging against the wheel the tire of which has considerable friction on the table causes the table to move transversely and carry the car sidewise in such a direction that on the continued forward movement of the car it will run centrally over the pit, or onto the trestle, or onto the elevator, regardless of the angle at which the car approaches and the wheel hits the deflecting roller and of the distance it is on one side or the 95 other of the center line of the pit, trestle or elevator. As the deflecting rollers turn freely and the table moves easily from side to side the car wheels do not ride up on the rollers but are guided to a practically 100 uniform position over the pit, or onto the trestle, or onto the elevator, before which this apparatus is placed. This apparatus is cheap to construct as it is made up of readily obtained elements, and it is simple to install 105 in the desired place of use. The elements are assembled and the apparatus is shipped and installed in place of use as a unit and when located it eliminates all danger of a car dropping into a pit or off from a trestle. 110

The invention claimed is:

1. An apparatus for guiding an automo-

bile into service position comprising a table mounted to move transversely across the service position and freely rotating rollers fixed in position and extending obliquely across said table.

2. An apparatus for guiding an automobile into service position comprising a frame, a table movable lengthwise of the frame and freely rotating rollers mounted in bearings fixed to the sides of the frame and extending obliquely across the table.

3. An apparatus for guiding an automobile into service position comprising a frame, angularly arranged freely rotating rollers mounted on the frame and a table supported by the frame and movable transversely of and beneath said rollers.

4. An apparatus for guiding an automobile into service position comprising a frame, rolls supported by the frame, a table movably mounted on said rolls and angularly related rollers mounted on the frame and extending obliquely across the table.

5. An apparatus for guiding an automobile into service position comprising a

frame, rolls supported by the frame, a table movably mounted on said rolls, springs arranged to normally retain the table centrally in the frame and angularly related rollers mounted on the frame and extending obliquely across the table.

6. An apparatus for guiding an automobile into service position comprising a frame, rolls supported by the frame, a table mounted on said rolls and movable in said frame, aprons extending from said table over the opening between the table and frame, and angularly related rollers mounted on the frame and extending obliquely across the table.

7. An apparatus for guiding an automobile into service position comprising a rectangular frame, shafts extending transversely of and mounted in the sides of the frame, rolls on said shafts, a table movably supported by said rolls, and angularly related rollers mounted on the sides of the frame and extending obliquely across the table.
